ATTORNEY.

UNITED STATES PATENT OFFICE.

JOHN WOEK, OF CANTON, OHIO, ASSIGNOR TO THE CANTON STEEL ROOFING COMPANY, OF SAME PLACE.

EAVES-TROUGH.

SPECIFICATION forming part of Letters Patent No. 434,310, dated August 12, 1890.

Application filed May 1, 1890. Serial No. 350,185. (No model.)

To all whom it may concern:

Be it known that I, JOHN WOEK, a citizen of the United States, residing at Canton, in the county of Stark and State of Ohio, have 5 invented certain new and useful Improvements in Eaves-Troughs; and I do hereby declare that the following is a full, clear, and exact description of the same, reference being had to the annexed drawings, making a part 10 of this specification, and to the letters of reference marked thereon, in which—

Figure 1 is a view of a portion of a sheet, showing its form before it is folded. Fig. 2 is a view of a portion of a section of an eaves-trough, showing it properly folded to receive the end of an adjacent section. Fig. 3 is a 15 perspective view of the end of one of the sections, showing the same properly folded to receive and hold an adjacent section. Fig. 4 is a view of the end of a portion of a section, showing the bead in a different position. Fig. 5 is a view of a portion of a section to be 20 received in the folded end of its adjacent section. Fig. 6 is a view showing the sections 25 placed into position to be locked together.

The present invention has relation to eaves-troughs; and it consists in the different parts and combination of parts hereinafter described, and particularly pointed out in the 30 claims.

Similar letters of reference indicate corresponding parts in all the figures of the drawings.

In the accompanying drawings, A represents the eaves-trough sections, which may 35 be formed of any desired length or size. One end of each of the sections A is provided with the narrowed extension a, which extension is folded against the section A on the dotted line x x and a portion of said narrowed extension again folded against itself on the line y y, thereby forming the groove b and the guide b', which guide b' extends a short distance beyond the end of the section A, as 40 illustrated in Figs. 2, 3, 4, and 6. For the purpose of easily entering the sections the end of the section A which extends beyond the narrowed extension a is cut or formed at an angle to the balance of the end of said 45 section A, thereby forming the end of the bead c obliquely to the end of the section A and at the same time exposing to view a portion of the lip d.

It will be understood that by my peculiar formation I am enabled to partially enter 55 one end of the bead c into the adjacent end of the bead c before or in advance of the entrance of the end of the section A into the groove b, thereby making it easy to unite the sections A together. For the purpose of assisting 60 the entrance of the section A the outer end of the narrowed extension a is inclined, as illustrated in Fig. 1.

The extension B is for the purpose of assisting in securely holding the sections A together and at the same time prevent any sagging of the trough proper at its joints.

It will be understood that in use the section A should be extended to the extreme end 70 of the groove b.

It will be understood that by forming one end of the bead c obliquely or spirally the operator will be enabled when connecting the sections A together to see when the lips d and the beads c are in proper relation to each 75 other to unite or lock the sections A together.

If desired, the narrowed extension a may be extended or cut beyond the dotted line x x, thereby extending the bead c past or beyond 80 the groove b.

Having fully described my invention, what I claim as new, and desire to secure by Letters Patent, is—

1. The combination of the sections A, provided with the bead c, having an oblique end, 85 and the narrowed extension a, bent to form the groove b and the guide b', substantially as and for the purpose specified.

2. The section A, provided with the bead c, having one of its ends formed obliquely to 90 the end of the section, and the lip d, substantially as and for the purpose specified.

3. The sections A, provided with the bead c, and having one end of the bead c cut or formed obliquely to the end of the section A, 95 substantially as and for the purpose specified.

In testimony that I claim the above I have hereunto subscribed my name in the presence of two witnesses.

JOHN WOEK.

Witnesses:

GRACE E. KEYES,
F. W. BOND.
